J. A. Humphrey

Designer,
G. C. Wright.

UNITED STATES PATENT OFFICE.

GEORGE C. WRIGHT, OF NEW YORK, N. Y., ASSIGNOR TO E. S. HIGGINS & CO., OF SAME PLACE.

DESIGN FOR CARPET.

Specification forming part of Design No. 6,137, dated September 10, 1872.

Specification describing a Design for Carpets, invented by GEO. C. WRIGHT, of New York, county of New York and State of New York.

The nature of my design is fully represented in the accompanying photographic illustration, to which reference is made.

C represents a frame-work composed of scrolls and Grecian squares *c c d d*, and ornamental heading *e e*, surrounding ground A, and forming, with outline *b*, the inner ground F; G, a Grecian figure resting upon ground F; *f f*, scroll running from band C into ground A; B B, panels lying at an angle of forty-five degrees with C; B^x B^x, duplicates of B B, perpendicular with panel formed by band C; D, a Grecian band surrounding panels B B B^x B^x; E E, a circular figure with band in regular tracing, a modification of shield and dart, a small set figure resting upon center of E, in character with the style of design; d^x d^x d^x, flowers and leaves of Persian type. I prefer to make A, green; C e, yellow and brown; B B^x, scarlet ground, with bands in

yellow and brown; F, white; E, yellow and brown; d d, green and blue; H, a mottled ground, composed of blue, red, brown, drab, and white dots. I do not consider the colors selected to be an essential element in my design. I am aware that carpet-patterns composed of bands, Grecian borders, scrolls, and flowers is not new, and lay no claim to those features.

The distinctive character of my design is found in the construction of bands, Greek work, flowers, &c., with panels and circles inwrought as illustrated, and all resting upon a mottled ground.

What I claim as my invention is—

A design for carpet, in which the panels, bands, flowers, circles, and mottled ground are combined, substantially in the manner above described.

GEO. C. WRIGHT.
